(57) **CLAIM**

The ornamental design for a transducer-protector for medical haemodialysis lines, as shown and described.

DESCRIPTION

FIG. 1 is a perspective view of the top, front and left side of a transducer-protector for medical haemodialysis lines showing my new design;

FIG. 2 is a perspective view from the bottom, front and right side thereof;

FIG. 3 is a perspective view from the rear view thereof;

FIG. 4 is a side elevational view, the opposite side being a mirror image thereof; and,

FIG. 5 is a front elevational view thereof.
